PLASTIC KNIFE

Hubert E. Christian, 4019 E. Fairmount, 85018, and
David W. Lee, 1606 E. Borghese Place, 85016, both
of Phoenix, Ariz.

Filed May 21, 1973, Ser. No. 362,356

Term of patent 14 years

Int. Cl. D7—03

U.S. Cl. D7—138

FIG.—5 FIG.—1 FIG.—2 FIG.—3 FIG.—4

FIG.—6

FIG.—7

FIG. 1 is a side elevational view of a plastic knife showing our new design;

FIG. 2 is an opposite side elevational view thereof;

FIG. 3 is a top plan view thereof;

FIG. 4 is a bottom plan view thereof;

FIG. 5 is a front end view thereof on an enlarged scale;

FIG. 6 is a rear end view thereof on an enlarged scale; and,

FIG. 7 is a cross-sectional view thereof on an enlarged scale, taken along the line 7—7 in FIG. 1.

We claim:

The ornamental design for a plastic knife, substantially as shown and described.
